HOODED GARMENT

Filed April 29, 1937

UNITED STATES PATENT OFFICE

2,102,251

HOODED GARMENT

Morris Arst, Chicago, Ill.

Application April 29, 1937, Serial No. 139,655

2 Claims.

(Cl. 2-84)

This invention relates to hooded garments, such as men's, women's and children's mackinaws, hunting and fishing coats, snowsuits, rain-coats, dress coats and the like, and is in the nature of an improvement upon the combined coat and cap shown and described in my prior Patent No. 1,972,585 dated September 4, 1934.

In the garment illustrated in my prior patent, the hood is composed of two separate hood sections sewed to the collar of the garment and the two hood sections are provided on the edges thereof, which meet to form the completed hood, with hookless fasteners, such as the "zipper", for securing the edges together after the sections have been withdrawn from the space provided for the storage of the hood sections when not in use. It has been observed that the two hood sections were not always neatly replaced in the space provided therefor, and, as a result, unsightly bulges were produced in the back of the garment by the carelessly replaced hood sections. Furthermore, it requires manipulation to secure the two hood sections together after they have been drawn over the head of the wearer.

One of the objects of the present invention is to simplify and otherwise improve on the construction of the hood. Another object is to form the hood complete so that no fastening means are required for detachably fastening together the two hood sections, as in my prior patent. Another object is to provide a hood of novel construction and containing an upright box pleat whereby the hood may lie flat or remain in a smooth condition when concealed in the space provided for it in the garment, thereby avoiding the possibility of any unsightly bulges in the back of the coat, and which hood when withdrawn from said space may be opened up and placed upon the head of the wearer without the necessity of fastening together any sections thereof.

Other objects and advantages will appear in the course of this specification and, with all of said objects and advantages in view, this invention consists in the several novel features of construction, arrangement and combination of parts hereinafter fully set forth and claimed.

The invention is clearly illustrated in the drawing accompanying this specification in which:

Fig. 1 is a front elevation of a hooded garment embodying a simple form of the present invention and showing the hood in place upon the wearer.

Fig. 2 is an enlarged, fragmental, rear elevation of the upper portion of the garment laid

out flat with the hood extended from the collar.

Fig. 3 is a view similar to Fig. 2 but showing the hood concealed in the garment and showing a portion of the undercollar and back of the garment broken out to illustrate the hood.

Fig. 4 is a plan of a top section and a side section of the hood which comprises one-half of the hood, the sections being laid out flat.

Fig. 5 is a diagrammatic, horizontal section taken on the line 5-5 of Fig. 2.

Fig. 6 is a diagrammatic, vertical cross-section taken on the line 6-6 of Fig. 2.

Fig. 7 is a view similar to Fig. 6 but showing the hood concealed in the space provided for it.

Referring to said drawing, which illustrates a simple embodiment of the invention, the reference characters 10-10 designate the front pieces, 11 the back, 12 the collar, 13-13 the sleeves, and 14 the lining of a coat or other garment of similar nature. As is customary, the collar comprises a top collar portion 15 which is sewed to the upper edge of the lining at *b* and an undercollar portion 16 which is sewed along its lower edge to the upper edge of the back of the garment as at *a*, thereby providing a space *c* for the reception of the hood.

The undercollar portion 16 is provided with a slit 17 running lengthwise of the collar adjacent its outer long edge, and this slit is held in closed condition by suitable fastening means, here shown as a hookless fastener or "zipper", as it is commonly called, one element 18 thereof being secured along one edge of the slit and the companion element 19 being secured along the other edge thereof. The usual slide 20 is provided in connection with the fastening elements for coupling the companion elements of the fastener together when the slide is slid along in one direction, and when slid along the other direction, the slide disconnects the coacting fastening elements, as is well understood by those skilled in the art to which this invention pertains.

The zipper form of fastener is preferred because it is simple and easy to manipulate and completely closes the slit.

Secured to the edge portion adjacent the slit 17 on the inner side of that part of the undercollar, which is next adjacent to the back 11, is a completely formed hood 21, which can be inserted into the space between the top and undercollar portions and between the back and the lining to conceal the hood from view when it is not being worn. When the slit is open the hood may be withdrawn from said space and opened out into condition for use. At its base or neck

portion 22 the width of the hood is slightly less than the length of the slit 17 as is seen in Fig. 2, this width being sufficient to bring the sides of the hood (when worn) over the cheeks of the wearer.

In order to permit the hood to assume a flat or smooth condition when concealed in the space provided for it in the garment, and thereby prevent the formation of unsightly bulges at the 10 back of the coat, the hood is constructed in a particular manner which will now be described:

Desirably four pieces of material are required to make the complete hood, two of which are seen at 23, 24 in Fig. 4. The other two pieces 15 are similar to the ones shown. Each of the side sections 23 has a substantially straight lower edge 25 which is located at the base or neck portion of the hood and comprises the edge which is stitched to the collar. From one end of the 20 lower edge, one side edge 26 extends substantially at right angles to the lower edge in an inwardly curved line as shown, which becomes sharper towards its upper end. From the upper end of the edge 26 the top edge 27 curves convexly, upwardly and then downwardly toward the back (forming part of the crown), and this curved edge is carried down at the back in a convexly curved line as at 28, and terminates at the other 25 end of the lower edges 25.

The section 24 is of curved and elongated shape, its upper edge being convexly curved as at 30 and its lower edge being inwardly curved as at 31. The end edge 32 is curved inwardly and forms a continuation of the upper end of the 35 curved edge 26 of the side section. The other end edge 33 is substantially straight and forms the continuation of the lower edge 25 of the side section. The edges 27, 31 are sewed together along the dotted lines which represent the seam 40 between the sections. When sewed together these two sections form one-half of the hood. Two such halves are constructed, one for the right side and one for the left side, and the two halves sewed together along the edges 30 of the 45 two sections, after which the front edges 26, 32 are hemmed, thus forming the completed hood. The hemmed edge comprises the front edge of the hood. After the two halves have been sewed together, the base part is laid out flat and the 50 material of the back of the hood is folded upon itself to form a box pleat 34 (see Figs. 2 and 5) which runs practically from the top of the hood to the base thereof. In this flat condition the hood is pressed so as to set the box pleat, and, 55 desirably, the side edges are pressed so as to provide sharp creases at the side edges of the flattened hood. Thereafter, the lower edges 25, 33 of both halves are sewed to the inner side of the undercollar portion at the lower edge of 60 the slit, as viewed in Fig. 3, the front part of the hood facing the back of the coat. By constructing the hood from pieces of material substantially like those illustrated in Fig. 4, and by forming the box pleat in the back of the hood, it tends 65 to retain its flat or smooth shape, and when inserted into the space provided for it in the garment, it remains flat or smooth therein, thereby avoiding any unsightly bulges in the back of the coat.

Fig. 3 shows the hood concealed in the space provided for it, and it shows the slit 17 in the undercollar portion closed by the "zipper". In this condition the coat may be worn with the

collar turned up or the collar may be turned down in the customary manner.

To use the hood, the slide of the "zipper" is slid to the other end of the slit, thereby opening it and the hood is withdrawn to the position shown in Fig. 2 and, after the coat has been placed upon the wearer, the hood may be opened out and placed upon his head. When the hood is replaced in the space provided for it, the box pleat tends to resume its shape, thereby enabling the hood to lie or extend in a flat or smooth condition in the space provided for it.

The hood and the goods of the coat are desirably formed from the same material, which is usually heavy. For this reason the ordinary hood cannot be stored in a smooth condition in the space provided for it in the garment.

When the hood is used in connection with a garment which is not provided with a lining, the hood constructed in accordance with the above 2 description may lie flat or smooth on the inner side of the back.

I claim as new and desire to secure by Letters Patent:

1. A hooded garment having a back and a lining therefor, and a collar having a top collar portion sewed to the lining and an undercollar portion secured to the back, said collar, back and lining providing a storage space for a hood, the undercollar portion having a lengthwise extending slit therein, fastening means for closing said slit, and a completely formed hood, with the front and back thereof folded together at the sides, and having an upright box pleat in its back, the hood being pressed flat to form creases along the marginal edges thereof and at the box pleat, said hood being stitched along its neck portion to the collar, on the inner side thereof, adjacent the slit therein, and capable of being stored in said space in a smooth condition. 40

2. In a hooded garment, a coat having a back and its lining, and top and undercollar portions forming its collar, the top collar portion being secured to the upper edge of the lining and the undercollar portion being secured to the upper 45 edge of the back, thereby forming a space for the storage of a hood, one of said collar portions having a slit therein extending lengthwise of the collar, fastening means for closing said slit, and a complete hood having a neck portion secured to one portion of the collar on its inner side, adjacent the slit, the hood being composed of oppositely disposed side sections, doubled upon themselves at the sides of the hood and forming 50 sides and back parts of the hood, the upper and rear edges of said side sections being convexly curved, and curved, elongated sewed together middle sections which are sewed together along their convex edges and sewed along the concaved edges to the top and back convexly curved edges 60 of the side sections and comprising top and intermediate back parts of the hood, said middle sections having a box pleat running lengthwise thereof, and the front and back of the hood being folded together at the side edges and pressed flat, whereby the hood is capable of being stored 65 in a flat condition in said storage space, the hood also being capable of being withdrawn from said space and extended into a shape conforming generally to the head of the person wearing the 70 garment.

MORRIS ARST.
